Attorney.

UNITED STATES PATENT OFFICE.

JOSEPH B. ROSE, OF WHEELING, WEST VIRGINIA.

GAGE.

1,333,996.

Specification of Letters Patent. Patented Mar. 16, 1920.

Application filed February 10, 1919. Serial No. 275,955.

To all whom it may concern:

Be it known that I, JOSEPH B. ROSE, a citizen of the United States of America, and resident of Wheeling, county of Ohio, and State of West Virginia, have invented certain new and useful Improvements in Gages, of which the following is a specification.

This invention relates broadly to gages, and more particularly to a gage for carpenters' use in laying out hinge mortises in doors.

The primary object of the invention is to provide an extremely simple and inexpensive tool which is adapted to be applied to the edge of a door or to the face of a door jamb, and which, when so applied, presents edges in position to be followed with a scribing-awl or other pointed instrument for accurately marking the outlines to be followed in cutting a hinge mortise.

A further object is to provide a tool of the character mentioned adapted to be employed for simultaneously indicating the length, width and depth of the mortise to be formed, so that all necessary outlines may be marked by a single operation, or without moving or changing the position of the tool.

A further object is to provide a tool which may be firmly and conveniently held in position with one hand while employing the other hand to mark the outlines.

And a still further object within the contemplation of the invention is to provide a gage of the character mentioned which also serves as a gage by means of which a door-casing may be accurately set or positioned with respect to the door-jamb.

In describing the invention in detail, reference is herein had to the accompanying drawings, in which—

Figure 1 is an end elevation of the invention;

Fig. 2 is a perspective view of the same applied in operative position to the edge of a door; and—

Fig. 3 is a perspective view illustrating the application of the device as a gage for setting a door-casing.

Referring to said drawings, in which like designating characters distinguish like parts throughout the several views—

1 indicates the main body portion of the device, the same consisting of a thin flat plate of metal of rectangular form which

has a length corresponding to that of the hinge-leaf for the reception of which the mortise is to be formed in the edge of a door, as 2. One of the lateral edges of said plate 1 is turned at right angles to the plate, forming a longitudinally extending lateral flange 3 the width of which corresponds with the thickness of said hinge-leaf and, consequently, with the depth of the mortise to be formed. The width of the plate from the inner face of the flange 3 to the opposite lateral edge of the plate corresponds with the width of the mortise to be formed.

Carried on the outer face of the plate 1, preferably in a central position, is a knob 4 by means of which the device may be held in place while a scribing-awl or other pointed instrument is being passed around the edges of the device to mark the outlines of the latter for visually indicating the boundaries of the mortise to be formed. The preferred form of knob is depicted in the drawings, the same consisting of a cylindrical shank or neck-portion 4^a, an integral reduced stem 4^b at the inner end of said shank disposed in threaded relation to the plate 1, and an integral enlarged outer end or head portion 4^c with inwardly inclined or curved surface walls meeting and merging with those of said shank or neck-portion 4^a. In practice, said shank or neck-portion is held between the first and second fingers of a hand of the user, with the backs of said fingers resting upon the plate 1 and with the ball of the thumb of said hand resting in a shallow concave seat or socket 4^d provided therefor in the outer face of said knob. As is obvious, an extremely convenient means of holding the device firmly in operative position is afforded by the form of knob described.

To adapt the tool for use as a gage for accurately setting door-casings, two or more stops 5 are mounted on the outer face of the plate 1 in a line parallel to that lateral edge of the plate which is opposite the flange 3 and at a distance from said edge equal to the distance (ordinarily about five-sixteenths of an inch) which it is desired shall intervene between the inner edge 6^a of the door-casing 6 and the face of the door-jamb 7. In applying the tool to this use the outer face of the plate 1 is set against the edge of the door jamb 7 with the posts 5 resting firmly against the face of said jamb, as shown in Fig. 3.

With the device held in this position, the door-casing 6 may be set in place with its edge 6^a abutting the edge of said plate, or said edge may be employed as a straight edge for marking on the edge of the jamb the line to which the casing is to be set.

From the foregoing it will be understood that the device constitutes a very simple, cheap and convenient tool for carpenters' use, adapted both for gaging hinge-mortises and for gaging the setting of door-casings.

What is claimed is—

1. A gage comprising a rectangular plate which constitutes a straight edge for marking the outlines of a hinge mortise, said plate having an inwardly directed right angle flange along one of its lateral edges adapted to form a depth gage for such mortise, and means carried upon the outer face of said plate parallel to and at a spaced

distance from the unflanged edge of said plate to form a door casing gage.

2. A gage comprising a rectangular plate which constitutes a straight edge for marking the outlines of a hinge mortise, said plate having an inwardly directed right angle flange along one of its lateral edges adapted to form a depth gage for such mortise, a plurality of stops rigidly carried in alined relation upon the outer face of said plate parallel to and at a spaced distance from the unflanged edge of said plate to form a door casing gage.

In testimony whereof, I affix my signature in presence of two subscribing witnesses.

JOSEPH B. ROSE.
